US00D915943S

(12) **United States Design Patent** (10) Patent No.: **US D915,943 S**
Choi (45) Date of Patent: **** Apr. 13, 2021**

(54) **AUTOMOBILE**

(71) Applicants: **Hyundai Motor Company**, Seoul (KR); **Kia Motors Corporation**, Seoul (KR)

(72) Inventor: **Hong Seok Choi**, Incheon (KR)

(73) Assignees: **Hyundai Motor Company**, Seoul (KR); **Kia Motors Corporation**, Seoul (KR)

(**) Term: **15 Years**

(21) Appl. No.: **35/508,312**

(22) Filed: **Jul. 10, 2019**

(80) **Hague Agreement Data**

Int. Filing Date: **Jul. 10, 2019**
 Int. Reg. No.: **DM/202618**
 Int. Reg. Date: **Jul. 10, 2019**
 Int. Reg. Pub. Date: **Jan. 10, 2020**

(30) **Foreign Application Priority Data**

Feb. 27, 2019 (KR) 30-2019-0009038

(51) LOC (13) Cl. **12-08**

(52) U.S. Cl.

USPC **D12/92**
